UNITED STATES PATENT OFFICE.

JOHN CHAFER, OF CLEVELAND, OHIO.

VENTILATOR.

1,247,639.

Specification of Letters Patent. Patented Nov. 27, 1917.

Application filed December 30, 1915. Serial No. 69,328.

To all whom it may concern:

Be it known that I, JOHN CHAFER, a citizen of the United States of America, residing at Cleveland, in the county of Cuyahoga and State of Ohio, have invented certain new and useful Improvements in Ventilators; and I hereby declare the following to be a full, clear, and exact description of the invention, such as will enable others skilled 10 in the art to which it pertains to make and use the same.

This invention relates to new and useful improvements in revolving chimney cowls or ventilators.

15 The object of the invention is to provide an improved ventilator for use on chimneys or stacks of buildings and the like which will afford a thorough ventilating means and will at the same time prevent rain or 20 moisture from entering the chimney or stack.

My invention, therefore, consists in the features of construction and combination of parts, hereinafter described in the specification, particularly pointed out in the claims 25 and illustrated in their preferred form in the accompanying drawings.

Referring to the accompanying drawings, Figure 1 is a top plan view of a ventilator embodying my invention. Fig. 2 is a side 30 elevation of the same showing also a portion of the stack on which the ventilator is mounted. Fig. 3 is a section on line 3—3, Fig. 2. Fig. 4 is a section on line 4—4, Fig. 2.

35 The ventilator comprises a hollow oblong casing 10 which is entirely open at each end and is in general rectangular in cross section. The casing is slightly larger at one end, which may be termed the air inlet end, 40 than it is at the opposite end, which may be termed the outlet end. On the bottom of the casing and approximately central thereof is rigidly mounted a sleeve 11 which is adapted to fit down over the upper end of the stack or 45 chimney, shown at A, so that the sleeve may turn freely thereon. Near the upper end of the stack is secured a support in the form of a spider 12 in which is rigidly mounted a vertical shaft or spindle 13. The upper 50 end of the spindle is preferably pointed and on the bottom of the ventilator casing is secured a socket 14 adapted to receive the end of the spindle and form a bearing for the casing. A bearing 15 for the spindle is secured near the top of the stack and another bearing 16 is arranged on the spindle

within the sleeve. The ventilator casing is therefore mounted so as to rotate freely on the stack and change its position according as the direction of the wind changes. On 60 top of the ventilator casing is mounted a vane 17 in the usual manner.

In the bottom of the ventilator casing at each side thereof and near the center is formed an oblong or elliptical shaped opening 20, but otherwise the bottom of the ventilator is imperforate. At diametrically opposite sides of the sleeve 11 and in vertical alinement with the openings 20 in the bottom of the casing are formed openings 21. 70 Curved pipes 22 extend from the openings in the sleeve to the openings in the bottom of the casing. Within the casing are arranged two partition walls 23. Each wall starts at one side edge of the casing at the inlet or 75 mouth of the casing and then curves for a short distance and then extends approximately parallel with the sides of the casing to a point slightly beyond the openings 20. The said partitions therefore form a central funnel shaped chamber 24 and two side 80 chambers 25 which include the openings 20. The central chamber is the inlet chamber; the side chambers 25 are the vacuum chambers, and the common chamber 26 at the outlet end is the suction chamber. Brace walls 27 are preferably arranged between the side walls of the casing and the partition walls 23 which serve to strengthen the partition 85 walls and also reduce the size of the suction 90 chambers.

The operation of my improved ventilator is as follows:—The wind or air enters the ventilator casing at the mouth of the funnel shaped inlet chamber and passes through 95 said chamber into the suction chamber and then out at the outlet end of the casing. As the wind leaves the inlet chamber and passes into the suction chamber the air is sucked out of the side chambers 25 creating a 100 vacuum therein, and the air from the interior of the building is drawn up through the openings 20 and mingles with the air passing through the suction chamber and passes out through the outlet of the ventilators. By my arrangement of the partition walls within the ventilator casing it is impossible for rain or snow to enter the stack and any moisture entering through the mouth of the ventilator casing is carried 105 straight through the casing and out at the outlet end of the casing.

What I claim is:—

1. The combination with a stack, of a ventilator casing rectangular in cross-section and having an inlet opening at one end and an outlet opening at the opposite end, the outlet opening being smaller than the inlet opening, partition walls arranged within the casing and extending from top to bottom of the casing, said partition walls at the inlet end being arranged to contact with the side walls of the casing and being spaced from the side walls at the outlet end of the casing, said partition walls dividing the interior of the casing into an inlet chamber, a vacuum chamber arranged at each side of the inlet chamber and a suction chamber arranged at the outlet end of the casing and communicating with the inlet chamber and the vacuum chambers, each vacuum chamber having an opening in the bottom wall thereof, a sleeve mounted on the bottom of the casing, said sleeve having openings at diametrically opposite sides thereof and pipes connecting the openings in the vacuum chambers with the openings in said sleeves.
2. The combination with a stack, of a ventilator casing rectangular in cross-section and having an inlet opening at one end and an outlet opening at the other end, the outlet opening being smaller than the inlet

opening, a sleeve arranged on the bottom of the casing and adapted to receive the upper end of the stack, said sleeve having openings at diametrically opposite sides, means arranged in the stack for rotatably supporting said casing, said casing being provided with openings in the bottom thereof near each side, pipes extending from said openings in the bottom of the casing to the openings in the sleeve and partition walls arranged within the casing and extending from top to bottom thereof, said partition walls dividing the interior of the casing into a funnel-shaped central chamber which extends from the inlet end of the casing to a point beyond the center of the casing, two side chambers, said side chambers being arranged to include the openings in the bottom of the casing and a chamber at the outlet end of the casing in open communication with the central chamber and the two side chambers.

In testimony whereof, I sign the foregoing specification, in the presence of two witnesses.

JOHN CHAFER.
